C. W. WHITE,
COMBINED FOLDING AND RIGID LADDER,
APPLICATION FILED MAY 14, 1915.

Patented Mar. 28, 1916.

UNITED STATES PATENT OFFICE.

CHARLES W. WHITE, OF EAST ST. LOUIS, ILLINOIS.

COMBINED FOLDING AND RIGID LADDER.

1,177,557.

Specification of Letters Patent. Patented Mar. 28, 1916.

Application filed May 14, 1915. Serial No. 28,198.

To all whom it may concern:

Be it known that I, CHARLES W. WHITE, a citizen of the United States, and resident of East St. Louis, Illinois, have invented 5 certain new and useful Improvements in Combined Folding and Rigid Ladders, of which the following is a specification containing a full, clear, and exact description, reference being had to the accompanying 10 drawings, forming a part hereof.

My invention relates to improvements in ladders, and the object of my invention is to construct a ladder of a number of hinged sections whereby it may be folded to occupy 15 a minimum of space when not in use, and to the end that it may be carried to places for use where a non-folding ladder could not be carried; to provide hooks for the suspension of the ladder for certain uses and to 20 provide means at the hinging points of the ladder section for locking the sections to form a rigid ladder which may be extended to an overhead point from the folded position.

With the above object in view, my invention 25 consists of certain novel features of the construction and arrangement of parts hereinbefore fully set forth, pointed out in my claim and illustrated by the accompanying 30 drawings, in which:

Figure 1 is a perspective of the ladder suspended from an overhead point; Fig. 2 is a perspective of the ladder, partly 35 folded, and partly extended, the extended part having its sections locked; and Fig. 3 is a sectional elevation of the hinge and lock.

Referring by numerals to the accompanying drawings, 5 and 6 designate the side pieces of the ladder, each of which comprises 40 a number of sections whose ends overlap and which overlapped ends are relatively hinged upon rounds 7.

As shown in Fig. 3, the ends 8 of the 45 rounds are reduced to receive the overlapped ends of the side pieces, which are coincidentally perforated whereby to journal upon the reduced ends of the rounds. The ends of the rounds after receiving the sides are upset or riveted to hold the sides in place.

By this arrangement the ladder comprises 50 a series of sections each of which consists of a pair of side pieces and a round, and it is to be observed (see Fig. 2) that the side pieces of alternate sections have their ends 55 occupying the first positions on the journal ends of the rounds and the ends of the re-

maining side pieces occupy the second positions on the journal ends. By this arrangement the sections will interfold to occupy a minimum of space, the side pieces forming 60 two independent stacks. That is, at each side of the ladder the alternate side pieces, when folded, interpose independently of the remaining side pieces.

The side pieces at one end of the ladder 65 terminate in hooks 9, whereby the ladder may be suspended for use, as for fire escape purposes. In this instance the ladder may be folded when not used and by reason of its compactness may be readily stored at 70 some conveniently accessible place and be at all times ready for instant use.

In my drawings I have shown the fire escape as being secured in a window with its hooks engaging the inner facing of a window frame, the bodies of the first section resting on the window sill and the remaining sections hanging down the side of a building, and leading to a place of safety, such as a window below, as shown. 80

On one of the ladder sections, the side pieces carry spacers 10 which serve to hold the ladder from the wall of the building when suspended, whereby to afford a footing and grip upon the rounds, which otherwise might so closely approach the wall as to render such footing and grip extremely difficult, and descent upon the ladder more hazardous. 85

In Figs. 2 and 3 I show a means whereby 90 the ladder sections may be relatively locked against hinging, whereby to make the ladder rigid so that it may be bodily elevated to an overhead position and either suspended by its hooks or otherwise held, for ascension 95 thereupon. These locking means consist of a channel iron 11 carried by each round and a nut threaded to each round. This thread is preferably a fast thread and I have in building the ladders exercised great care in this thread cutting to insure freedom of movement of the nut over the thread of the round, so that the nut may "spin" from one position to another. 100

In the first and second sections of the ladder in Fig. 2, the locking channels are shown as embracing the overlapped ends of the side pieces and the nuts brought to positions hold the channels in place, while in the remaining sections the channels are freed 110 from the side pieces to permit articulation for folding purposes. 105

When folded completely the spacers 10 engage the inner faces of the innermost side pieces and the hooks 9 engage the outer faces of the innermost side pieces and thus the 5 ladder is held true and the hooks are by preference made to bear inwardly against the remaining side pieces to frictionally hold the ladder in a folded position.

Having thus described my invention, 10 what I claim as new therein and desire to secure by Letters Patent of the United States therefor, is:

A ladder comprising rounds and sectional 15 side pieces whose ends overlap and are pivotally secured to said rounds, means at the

ends of said rounds for preventing movement of the side pieces axially relative to the rounds, a channeled element pivotally carried by each round and free to move longitudinally thereof, whereby it may be 20 brought to engage or be free from said side pieces and a nut threaded to the round for engagement with the channeled element.

In testimony whereof, I have signed my name to this specification, in presence of 25 two subscribing witnesses.

CHARLES W. WHITE.

Witnesses:

E. L. WALLACE,
R. G. ORWIG.
